EXPANSIBLE REAMER

Filed July 23, 1926

UNITED STATES PATENT OFFICE

FLOYD S. HARTWELL, OF LAKEWOOD, CLEVELAND, OHIO

EXPANSIBLE REAMER

Application filed July 23, 1926. Serial No. 124,488.

My invention relates to combination boring and reaming tools and particularly to such as are employed in heavy foundry and other work which subjects the tool to unusual wear and strain. It is of course to be understood, however, that the invention is not limited to tools of this class, but also appertains to tools which are designed for lighter work.

In all inserted blade reaming and boring tools with which I am familiar the cutting blades are held in place by means of a multiplicity of locking or adjusting screws. Not only is it a painstaking and time consuming task to properly adjust the blades of such reamers, but further much difficulty is experienced in maintaining the desired adjustment, particularly when the tool is subjected to very heavy usage as for instance, furnace section reaming or the like. The strain of this hard and continued use causes the blades to become loose or unseated. Reaming machines commonly include four six blade reamers, the blades of each reamer being secured by not less than twelve holding screws making a total of forty-eight screws for each machine. The loosening and tightening of these screws, for even minor readjustment, results in a great loss of time as will be readily appreciated. Furthermore, a loss of adjustment of the blades while the tool is in use is likely to result in spoiling of the work.

It is therefore the primary object of my invention to overcome the aforementioned difficulties and to provide a novel blade fastening means which will eliminate the necessity for the numerous fastening screws or analogous elements of the prior art; one which will permit of ready adjustment or removal of the blades as occasion may require and which is adapted to hold the blades rigidly in a set position even when the tool is subjected to continuous and very heavy usage for a long period of time.

The invention also aims to provide a tool of this class which is of unusually simple and durable construction, comprising but a minimum number of easily assembled parts, and which will be relatively inexpensive to manufacture.

The various features of novelty which characterize the invention are pointed out with particularity in the claims annexed to and forming a part of this specification. However, for a better understanding of the invention reference should be had to the accompanying drawings in connection with the following descriptive matter, the drawings illustrating what I now regard as a preferred embodiment of the invention. It is of course to be understood, however, that I do not propose to limit myself to this disclosure but reserve the right to make such changes and modifications as fairly fall within the spirit and scope of the invention as claimed.

In the drawings,

Figure 1 is a vertical longitudinal sectional view through a reamer constructed in accordance with the invention;

Figure 2 is an end elevation of the improved reamer;

Figure 3 is a group perspective illustrating an expansible ring and one of the blades embodied in the invention.

I have shown, for the purpose of illustration, a tool of the shell type but it is to be understood that it is equally applicable to tools of the solid head type.

The reamer head proper, designated at 1, is of circular cross section, being provided with an externally threaded portion 2 extending from its rear end throughout the major portion of its length and terminating at a shoulder 3 from whence the wall of the head tapers forwardly and outwardly in frusto-conical fashion as indicated at 4.

The front end of the head is provided with a plurality of longitudinally extending and circumferentially spaced surface grooves 5 having undercut wall portions indicated at 5^a. These grooves 5 have sloping bottoms 5^b and increase in depth in the direction of the rear end of the head as clearly shown in Fig. 1, said groove terminating at a point intermediate the ends of the threaded portion 2. Cutting blades 6 are insertible in the grooves 5 from the outer ends and the major portions of the blades are substantially wedge shaped in cross section as shown in Fig. 2 whereby to slidably fit in said grooves.

As will be readily understood from inspection of Figure 1, radial adjustment of the cutters may be secured by sliding them inwardly or outwardly in their slots 5. The nut 7 upon the threaded portion 2 serves by engagement with the rear ends of the cutters to actuate the same to a desired position and also constitutes an adjustable stop or backing to sustain the axial thrust of the cutters when the tool is in use. To lock the adjusting nut 7 in place, I employ a lock nut 8 which is also threaded upon the portion 2.

It will be observed that the ring 9 can be sprung into the groove 10 very readily and the notches 9^a engaged with the cutters 6. This prevents rotation of ring 9 and the split 9^a will be alined with the hole in the end of the head which is designed to receive the screw 11. By this arrangement the assembly 20 of the device is greatly facilitated.

The frusto-conical forward end 4 of the head has its outer surface lying in a plane substantially parallel with the bottom walls 5^b of the slots 5 so as to make the undercut walls 5^a substantially uniform in area throughout their length. Thus when the cutters 6 are fully projected there will still be ample bearing surface to sustain the cutters in the cutting operation.

Figure 2 illustrates that the grooves 5 are arranged in circular series. To retain the cutters 6 tightly in their grooves in a desired set position I employ, instead of the usual multiplicity of holding and adjusting screws, 35 a split ring 9, the split being formed by taper reaming as suggested in Figure 3. The walls 9^a of the split converge in the direction of what I will call the rear edge of the ring, and each of these walls is preferably cut so 40 as to be arcuate in cross section.

The ring 9 is designed to be received within a circumferential groove 10 which is cut in the front end of the head and communicates with the grooves 5 through their bottom walls

45^b. As shown in Figure 2 the depth of the grooves 5 is such that the cutters 6 have their inner edges projecting slightly into the circumferential groove 10. Thus when the ring 9 is sprung into the groove 10 it will bear 50 against the bottoms of the cutters 6. To hold the cutters in a set position, the screw 11 working in a counter-bore 12 in the end of the head, is tightened so that its tapered head 12^a bears against the converging sides 9^a of 55 the split to spread the ring and force the cutters 6 radially outward to wedge them tightly between their undercut converging walls 5^a.

It is to be noted that the screw 11 serves to maintain the ring 9 in place. However, I 60 preferably provide the ring with a circumferential flange portion 9^b at its rear edge, this flange portion 9^b being engaged with a shoulder 10^a which is formed in the back of the groove 10 as shown in Figure 1. The ring 65 flange 9^b is cut away as indicated at 9^c to avoid

engagement with the respective cutters 6.

From the foregoing description read in connection with the accompanying drawing the various advantages and economies of my invention will be readily understood and appreciated by those skilled in the art. The cutters 6 can be readily adjusted from one position to another by simply loosening the screw 11 and manipulating the adjusting nut 7. There are no screws to become lost and the single locking means serves for all of the cutters.

Having thus described the invention, what is claimed is:

1. A reamer comprising a head having grooves in its outer surface and provided with undercut walls, said grooves being open at one end of said head and increasing in depth in the direction of their other ends, radially projecting cutters carried by said head and insertible in said grooves, the undercut walls of said grooves engaging said cutters to limit radial outward movement thereof, said head having a circumferential groove in its first mentioned end and communicating with said first named grooves, said circumferential groove having a lateral enlargement at its inner side defining a shoulder, a split clamping ring insertible in said circumferential groove and having lateral projections engageable with said shoulder to hold said ring in place, a wedge screw working in said head and bearing against the split ends of said ring for circumferentially spreading the same to frictionally engage said cutters transversely of their axes whereby to effect a binding of said cutters against the undercut walls of their grooves and lock them against movement, a backing nut threaded on said head and engaging the ends of said cutters for adjusting the same longitudinally in their grooves, and a lock nut for holding said backing nut in adjusted position.

2. A reamer comprising a head having grooves in its outer surface and provided with undercut walls, said grooves being open at one end of said head and increasing in depth in the direction of their other ends, radially projecting cutters carried by said head and insertible in said grooves, the undercut walls of said grooves engaging said cutters to limit radial outward movement thereof, said head having a circumferential groove in its first mentioned end and communicating with said first named grooves, said circumferential groove having a lateral enlargement at its inner side defining a shoulder, a split clamping ring insertible in said circumferential groove and having lateral projections engageable with said shoulder to hold said ring in place, a wedge screw working in said head and bearing against the split ends of said ring for circumferentially spreading the same to frictionally engage said cutters trans-

versely of their axes whereby to effect a binding of said cutters against the undercut walls of their grooves and lock them against movement, and a backing nut threaded on said head and engaging the ends of said cutters for adjusting the same longitudinally in their grooves.

3. A reamer comprising a head having grooves in its outer surface and provided with undercut walls, said grooves being open at one end of said head and increasing in depth in the direction of their other ends, radially projecting cutters carried by said head and insertible in said grooves, the undercut walls of said grooves engaging said cutters to limit radial outward movement thereof, said head having a circumferential groove in its first mentioned end and communicating with said first named grooves, said circumferential groove having a lateral enlargement at its inner side defining a shoulder, a split clamping ring insertible in said circumferential groove and having lateral projections engageable with said shoulder to hold said ring in place, and a wedge screw working in said head and bearing against the split ends of said ring for circumferentially spreading the same to frictionally engage said cutters transversely of their axes whereby to effect a binding of said cutters against the undercut walls of their grooves and lock them against movement.

4. A reamer comprising a head having grooves in its outer surface and provided with undercut walls, said grooves being open at one end of said head, radially projecting cutters carried by said head and insertible in said grooves, the undercut walls of said grooves engaging said cutters to limit radial outward movement thereof, said head having a circumferential groove in its first mentioned end and opening transversely into said first named grooves, a split clamping ring insertible in said circumferential groove, and means for expanding said ring to bear against said cutters transversely of their axes to rigidly bind and hold the same against movement in their grooves.

5. A reamer comprising an integral head having grooves in its outer surface and provided with undercut walls, said grooves being open at one end of said head and increasing in depth in the direction of their other ends, radially projecting cutters carried by said head and insertible in said grooves, the undercut walls of said grooves engaging said cutters to limit radial outward movement thereof, and a contractible clamping element within said head and engageable with said cutters through said grooves to urge the cutters against the undercut walls of said grooves for rigidly binding the same against movement in their grooves.

6. The combination with a reamer head, the radially projecting blades, and the means

for holding said blades against radial outward movement; of a split ring insertible in the end of said head and designed to bear against the inner edges of said blades for the full width thereof, means for expanding said ring to bind against the blades and hold them in place, said head having an annular groove for the reception of said ring, the back of said groove being provided with a shoulder, and said ring having a laterally projecting part designed to engage said shoulder whereby the ring and head will be held assembled.

7. The combination with a reamer head, the radially projecting blades and the means for holding said blades against radial outward movement; of a split ring insertible in the end of said head and designed to bear against the inner edges of said blades for the full width thereof, means for expanding said ring to bind against the blades and hold them in place, said means comprising a wedge member carried by said head and insertible between the split ends of said ring, and said wedge member serving to hold said ring and head assembled.

8. The combination with a reamer head, the radially projecting blades and the means for holding said blades against radial outward movement; of a split ring insertible in the end of said head and designed to bear against the inner edges of said blades for the full width thereof, means for expanding said ring to bind against the blades and hold them in place, said means comprising a wedge headed screw carried by said head and insertible between the split ends of said ring, and said wedge screw serving to hold said ring and head assembled.

9. A reamer head having longitudinally extending blade holding grooves, blades carried therein and retained thereby against outward radial movement, an expansible multiple blade clamping device comprising a split ring removably carried within said head, said head overlying and protecting said clamping means, the latter being contractible for insertion into said head from one end thereof to engage said blades to effect a binding thereof in the blade holding portions of said head, a radially extending outer flange portion carried by said blade clamping means, and the clamping means receiving opening of said head having recess to receive said flange portion whereby the ring will be removably locked within said head.

In testimony whereof I affix my signature.
FLOYD S. HARTWELL.
